 New York, N. Y., a corporation of New York

Application July 13, 1934, Serial No. 734,901

4 Claims. (235—61.6)

This invention relates to tabulating machines and more particularly to an improved form of accumulator for such machines. In the well known form of Hollerith accumulator the drive shaft is provided with a series of continually running clutch driving elements, one for each denominational order. The adding or indicating wheels are individually geared to driven clutch elements and these latter are tripped into engagement with their associated driving elements at differential times during the operation of the machine and thereupon rotate with the driving elements an amount depending upon the value to be entered. At a predetermined time all the 15 clutches are mechanically disengaged and the several adding wheels will have been displaced different amounts depending upon the time at which the associated clutches were engaged. The driving clutch elements are constantly rotating so that engaging and disengaging occur 20 while the parts are in motion and obviously the clutches are under a mechanical load when the disengaging action occurs. Further than this, it has been necessary to provide so-called over- 25 throw locks for the driven elements to prevent inertia carrying them beyond the point of disengagement all of which has imposed an additional load on the driving mechanism.

The object of the present invention is to accomplish the differential displacement of the adding wheels in a new and improved manner by so organizing the accumulator that disengaging of the clutches that have been tripped occurs 30 while they are at rest. This plan has many and important advantages and reduces considerably the wear on the moving parts of the machine.

By providing an intermittent drive for the driving clutch elements the latter are brought to a stand-still at the time of de-clutching so 35 that disengagement occurs without strain and since at such time the driven elements are also at rest, there is no possibility of overthrow and the overthrow locks may be dispensed with entirely.

According to another feature of the invention, the hitherto mechanical carry mechanism operative to add a unit to the next higher order whenever one order passes through ten has been replaced by electrical instrumentalities. This has 40 the effect of further reducing the hitherto heavy load on the machine which in rapid action may not be adequately sustained.

According to the improved arrangement of the accumulator the time element involved in de-clutching the driving clutch elements is obviated

and de-clutching may be effected at any time after the clutch shaft is brought to a standstill.

Various other objects and advantages of the invention will be obvious from the following particular description of one form of mechanism embodying the invention or from an inspection of the accompanying drawings; and the invention also constitutes certain new and novel features of construction and combination of parts hereinafter set forth and claimed.

In the drawings:

Fig. 1 is a central section of an accumulator.

Fig. 2 is a plan view of Fig. 1, showing several orders of the accumulator.

Fig. 3 is an outside view of the accumulator showing the clutch knock-out operating mechanism.

Fig. 4 is a detail of the intermittent driving gears for the accumulator drive shaft.

Fig. 5 is a time chart showing the timing relationship of several parts of the mechanism.

Fig. 6 is a diagram illustrating the circuit connections of the accumulator.

Figs. 7, 8, and 9 show the driving and driven gears in different operative positions.

The accumulator is provided with a series of index or number bearing wheels 10, each arranged with ten digit spaces, characters or type and adapted to be singly, successively, or simultaneously rotated by the driving mechanism to add columns of figures. Each wheel 10 has secured thereto a gear 11 which meshes with a gear 12 freely mounted upon clutch shaft 13. Gear 12 has integral therewith a plurality of teeth 14 which are adapted to be engaged by

teeth of clutch member 15 which is slidably mounted on shaft 13 but constrained to rotate therewith. Member 15 is normally held out of engagement with teeth 14 and permitted to move into clutching engagement whenever a corresponding magnet 16 is energized. There is a magnet 16 provided for each clutch 15 and these are arranged in two horizontal rows and staggered in position. For each magnet there is a vertical bar or rod 17 pivoted in the frame and

carrying an armature 18 facing a magnet pole so that, on energization of the magnet, its corresponding rod 17 will be partly rotated against the force of a spring 19. This movement of the armature 18 releases a clutch lever 20 having a

stop 21 with which the armature is in direct engagement. The lever 20 is thus normally latched and when released by the energization of magnet 16 is free to be moved sidewise about its pivot

45 50 55

According to the improved arrangement of the accumulator the time element involved in de-clutching the driving clutch elements is obviated

22 by leaf spring 23 which bears upon one extremity of the lever.

Lever 20 at its forward end engages with the groove of sliding clutch member 15 and causes the teeth thereof to be carried into engagement with corresponding teeth 14 on gear 12 and thus transmit motion to the index wheels 10.

It will be understood that the magnets 16 are energized by circuits completed through perforations in record cards of the well known Hollerith type wherein the locations of holes represent numbers and as the cards are moved in transit past analyzing devices the circuits are completed to energize the magnets 16. The time of engagement of the clutches on shaft 13 therefore depends upon the position of the holes causing engagement. Consequently, the corresponding index wheel will be turned through an arc proportionate to such time. In other words, if the hole in the card represents the numeral "5", the index wheel will be turned five digit spaces. If it is started from zero, the number it will display is "5" but should it start from any other number, say "7", then the number it will display is "2" but it will have moved the wheel of the next higher order of units one digit space through carry mechanism which will be described hereinafter.

Restoration of the clutches is effected by fingers 24 which are individually and adjustably mounted upon bar 25 mounted for horizontal reciprocation on arms 26. One end of the bar is also pivoted to the free end of an arm 27 secured to a vertical rod 28 whose other end carries an arm 29. A rod 30 carries a cam follower member 31 whose follower roller 32 cooperates with a cam 33 mounted upon shaft 34.

As the shaft rotates cam 33 will rock member 31 counterclockwise as viewed in Fig. 3 and a depending arm 35 thereof will through adjustable screw and nut connection cause rocking of arm 29 and its supporting rod 28. This action will cause movement of bar 25 and attached fingers 24 against the free ends of clutch levers 20 to re-latch the same on the armatures 18. Shaft 34 also carries a cam 36 which cooperates with a sliding plate 37 in which are mounted studs 38 which are adapted to cooperate with extensions of rods 17. The timing is such that just as levers 20 are restored by bar 25 plate 37 is moved to cause rocking of rod 17 whereby the armatures will be retracted from the magnets and relatching with stops 23 positively effected.

The accumulator is driven from main drive shaft 39 which is connected to the card feeding and other units of the machine and is in constant rotation. Shaft 39 carries a gear 40 meshing with a gear 41 on shaft 34 in such ratio that shaft 34 effects one complete revolution for each cycle of the machine. During the greater part of the cycle the clutches 15 may be tripped at differential times to start rotation of their respective index wheels. At a predetermined time thereafter the bar 25 is operated to effect de-clutching. Following this, those orders into which carrying is to be effected will be again tripped and, after they have turned their related wheels an additional space, will be again disengaged by the bar 25.

The shaft 13 is driven from shaft 34 through an intermittent gear connection as shown in Fig. 4. This connection comprises a driving gear 42 and a driven gear 43. Gear 42 is provided with sets of teeth 80 and 81 and arcuate plates 82 and 83 each coextensive with a section of the

gear having no teeth. Gear 43 is provided with a set of teeth 80a which mesh with teeth 80 and a set of teeth 81a which mesh with teeth 81. Gear 43 also carries plates 82a and 83a which cooperate with plates 82 and 83 respectively to hold gear 43 stationary during the periods when teeth 80, 80a and 81, 81a are out of mesh. The operation and the timing of this connection may best be understood in connection with the timing chart of Fig. 5. In this chart a cycle of operations is represented as divided in sixteen parts. Entering takes place and the clutches are tripped at times indicated along the line labelled "Adding clutches". The line labelled "Distributor" indicates the time at which the circuits are completed through the adding magnets which is some time before actual engagement occurs to provide for the necessary mechanical movement of the parts. During the entering period, the toothed portions 80, 80a of the gears 42 and 43 are in engagement and the shaft 13 is driven uniformly and in synchronism with the card feeding mechanism through shaft 39. At the point marked "11" on the chart the driven gear 43 will have come to rest while the plate 83 is in cooperation with plate 83a and the gears 12 and connected index wheels 10 which may be clutched to the shaft will come to rest therewith at which time amounts will have been entered in accordance with the time at which initial engagement of the clutches occurred. It is during this period when the shaft 43 is at rest, that the knock-out bar 25 is operated to cause de-clutching and the actuated wheels will accordingly remain in their displaced positions. After the de-clutching action, the teeth 81a of the driven wheel 43 are again picked up by the further teeth 81 on gear 42 and the clutch shaft is accordingly in motion at point 13 of the cycle. At this time, impulses are transmitted to magnet 16 for carry purposes and their corresponding clutches will again be tripped and their wheels 10 will rotate through one further space.

At "15" the driven gear 43 will again have come to rest due to cooperation of plate 82 with plate 82a, and while in such position the knock-out bar 25 is again operated to cause de-clutching of the parts. It will be appreciated, of course, that with the intermittent gear construction the stopping and starting of the shaft 13 occur with gradual deceleration and acceleration as indicated on Fig. 5, due to the coaction of the gear teeth so that there is no sudden jarring of the parts during stopping and starting. It will also be apparent that with the shaft 13 at rest during de-clutching that the driving strain on the clutch elements 15 is released so that disengagement occurs with a minimum of strain on the knock-out bar 25 and its driving mechanism.

The several relative positions of the gears 42, 43 are shown in Figs. 7, 8, and 9. In Fig. 7 the parts are shown in the position at which deceleration of shaft 13 commences. At this point the last of the teeth 80 is leaving the last of the teeth 80a and the leading edge of plate 83 has engaged plate 83a and will proceed to effect a camming action against the latter to bring it to the position of Fig. 8. This decelerating movement takes place during the period represented in Fig. 5 by the oblique line extending between the points labelled "Clutch shaft slows down" and "Clutch shaft stopped." Fig. 8 shows the position in which gear 43 is locked while gear 42 continues in its rotation and the locking, as seen, is due to the cooperation between plates 83a and 83 and 75

also between sections 90 and 91 of gears 43 and 42 respectively. In Fig. 9 is shown the position of the parts with gear 42 just about to pick up and advance gear 43. This is brought about by the wide leading tooth of group of teeth 81 with the edge of section 90. Due to the involute configuration of the engaging surfaces there is a resultant acceleration of gear 43 from rest position to the speed of gear 42, whereupon uniform driving speed is attained through engagement of the remaining teeth 81 with teeth 81a. This same sequence of operations is later repeated when plate 82 arrives in cooperative relationship to its companion plate 82a. Thus in the manner described gear 43 is driven with a uniform motion during the period when its teeth 80a and 81a are driven by teeth 80 and 81 respectively; is decelerated through the engagement of the leading edges of the plates 83 and 82 with plates 83a and 82a respectively; is accelerated by the engagement of the leading wide teeth 81 and 81a; and is held in rest position as explained in connection with Fig. 8.

Each index wheel 10 carries a commutator 44 having a conducting segment 45 which is adapted to form an electrical connection between a pair of brushes 46 whenever the wheel stands at "9." A cam 47 is also carried by the wheel 10 and this cam is adapted to rock a bell crank latching lever 48 to cause release of a contact blade 49 whenever the index wheel passes from "9" to "0." Blade 49 carries one of a pair of contacts 50 and when released by latch 48 will move against insulating bail 51 without, however, closing contacts 50. At the carry time in the cycle, bail 51 is moved toward the right as viewed in Fig. 2 and closure of contacts 50 will be effected in those positions in which the blades 49 have been released. This closure will complete the carry circuits as will be more specifically traced in connection with the circuit diagram.

Bail 51 is carried by arms 52 pivoted at 53, one of which is provided with a cam follower roller 54 cooperating with a cam 55 on a shaft 56 which has gear connection 57 with shaft 34. On shaft 56 are commutators 58, one for each order of the accumulator which are provided with contact segments 59 adapted to electrically connect brushes 60 during the carry portion of the cycle. The manner in which the carry circuits are completed may best be explained in connection with the circuit diagram (Fig. 6). This figure represents an adding machine and the various appliances and circuits used in operating it. Bearing in mind the manner in which these machines are habitually used and operated by punched cards, the numerals on which are indicated by the number and positions of the holes and are to be added, the following is the plan of operation. Start key contacts 63, when closed, complete a circuit from one side of line 64, through motor M, stop key contacts 65, start relay magnet 66, start key contacts 63, to other side of line 67. Start relay 66 closes its contact 66a to provide a holding circuit for the motor M through relay contacts 68a and cam contacts 69 in parallel. Contacts 68a are closed while record cards traverse the analyzing brushes of the machine and are closed under control of the so-called card lever contacts. When a punched card is inserted into the machine, it moves a lever 61 and closes contacts 62 thereby completing a circuit from line 64, relay magnet 70, relay magnet 68, contacts 62, to line 67, thereby causing closure of contacts 68a.

Assuming that the machine is operating and

cards passing through it; whenever an analyzing brush 71 encounters a perforation in a card, a path for the current is established to such counter magnet as may be determined by the position or column in which the perforation lies and the corresponding clutch is shifted into engagement and remains so during the adding portion of the cycle and until the clutches are knocked out of engagement. A representative adding circuit may be traced from line 64 to contacts 70a, cam contacts 72 and 73 which permit current to pass only during the card reading portions of the cycle, perforation in the record card, analyzing brush 71, plug connection, such as 74, adding magnet 16 to line 67. It will be observed that at the time 15 the clutches are first disengaged that the cycle of operations is not complete and carry operations are still to be performed. At the carry point in the cycle, cam contacts 75 are adapted to close and, in accordance with the conditions obtaining in the several orders of the accumulator, circuits will be completed to the adding magnets 16 in those positions in which an extra unit is to be added. In the diagram are shown four orders, in the units of which commutator 44 may be omitted since carrying is not effected in such order. The commutators, however, have been shown in dotted outline to indicate their location for certain cases where it might be desirable to carry a "1" into the units order. 30

Assuming that during adding operations the units order passed through zero, its contacts 50 will therefore be closed at the carry time and upon closure of contacts 75 the circuit will be completed from line 64, contacts 75, contacts 50 in the units order, wire 76, to adding magnet 16 of the tens order, and to line 67. If at such time the tens order wheel is standing at "9", the corresponding brushes 46 will be connected by segment 45 and the circuit through wire 76 will branch through brushes 60 and segment 59 of the tens order, brushes 46 and segment 45 of the tens order to magnet 16 of the hundreds order. After the carry circuits have been completed as selected by the condition of the index wheels, the circuits are broken by opening the contacts 75 and contacts 50 are again moved to their open, latched position by the restoring bail 51. 45

The index wheels 10 are freely mounted upon a shaft 77 which is provided with a notch 78 running parallel with the axis of the shaft. Each wheel carries a spring-pressed pawl 79 which, as the wheel is rotated to accumulate, is moved away from the notch in a counterclockwise direction so that after adding operations are completed the pawls 79 will occupy various positions about the periphery of shaft 77. When it is desired to reset the accumulator, the shaft 77 is given one complete turn in a counterclockwise direction during which the notch 78 will pick up the pawls 79 and therethrough return the wheels to their zero positions. Shaft 77 may be rotated manually or by automatic mechanism well known in the art which need not be described herein. 50 55 60 65

While there has been shown and described and pointed out the fundamental novel features of the invention as applied to a single modification, it will be understood that various omissions and substitutions and changes in the form and details of the device illustrated and in its operation may be made by those skilled in the art without departing from the spirit of the invention. It is the intention therefore to be limited only as indicated by the scope of the following claims: 70 75

What is claimed is as follows:

1. In an accumulator for a tabulating machine, an adding clutch, including an intermittently and cyclically operating driving element, means for causing the same to move and rest in alternation, means for causing engagement of said clutch at differential times during the movement of said driving element in each cycle of operation and means for causing disengagement thereof during the period in each cycle when the driving element is at rest.
2. In a cyclically operated accumulator for a tabulating machine, an adding element, a driving element therefor, means for moving said driving element with a uniform motion for a plurality of periods during each cycle and for bringing the same to rest after each movement, means for connecting said adding element to the driving element during any or all of said periods of motion and means for causing disconnection during each period of rest.
3. In a cyclically operated accumulator for a tabulating machine, an adding element, a driving

element therefor, means for moving said driving element with a uniform motion for a plurality of periods during each cycle, and for bringing the same to rest after each movement, record controlled means for connecting the adding element to the driving element during one of said periods of movement, carry mechanism for causing the adding element to be connected to the driving element during another period and means for causing disconnection during each period of rest.

4. In an accumulator for a tabulating machine, an adding clutch including a driven element and a driving element, a member integral with said driving element, a constantly rotating driving shaft, an intermittent gear device on said shaft for alternately operating said member and holding the same at rest, record controlled means for causing engagement of said elements while the member is in motion and a cam carried by said shaft for causing disengagement of said elements after the member has come to rest.

CLAIR D. LAKE.
